SACK BASKET

Helen King, Armour, S. Dak.

Application July 13, 1956, Serial No. 42,242

Term of patent 7 years

(Cl. D58—4)

Fig. 1.

Fig. 3.

Fig. 2.

I claim:

The ornamental design for a sack basket, as shown.
